12 Claims. (Cl. 200—153)

1

The invention is concerned with a device for protecting circuit breakers against unintentional closing of the contacts. Such unintentional closing may for instance occur when the circuit breaker or switch of any type, with at least one fixed or stationary contact and at least one movable contact, is employed in any switching apparatus, switch box, on a switch board, panel, or the like of a mobile station on any vehicle, ship, railroad, aircraft, or any other mobile conveyance which during its locomotion is exposed to vibrations or sudden shocks, such as from change of direction or speed or other causes.

If in the following specification and in the claims switch elements are designated as stationary, the term "stationary" is to be understood to relate to those parts which are fixed or permanently at rest at the switching apparatus and in the mobile vehicle which parts, however, of course move together with, but not relatively to, the mobile vehicle.

The contacts, opposite to, and cooperating with the stationary contact are the movable contacts, such as blades, knives, brush contacts, face contacts, or the like. The invention particularly relates to such movable contacts carried on a shaft through the turning of which the contacts are closed and opened. These contacts carried on a shaft may be the movable main contacts or the movable main contact of a circuit breaker or switch or they may be auxiliary contacts, or an auxiliary contact, such as conventional in the art or convenient for preventing the formation of the arc, or arcing the arc, or extinguishing or blowing out the arc.

The invention is concerned primarily with the actuating means of the movable contact or contacts in circuit breakers or switches of the aforesaid type and a primary object of the invention is a development of such actuating means which prevents the movable equipment or mechanism of the circuit breaker from, or protect it against, being moved unintentionally to such an extent that the movable contacts or contact might engage the stationary contacts or contact. Such unintentional engagement might occur when, during or through the operation of the vehicle or the like, vibrations or shocks are produced of an intensity sufficient to cause movement of the movable mechanism or equipment through its inertia relatively to the stationary contacts to an extent that the movable main contacts or arcing or other auxiliary contacts or contact engage, even if only transitorily, the stationary contacts or contact and the current is switched on, if even to be interrupted immediately thereafter,

2

It is thus an object of the invention to provide the actuating means of the movable equipment of the circuit breaker or switch with an impeding mechanism which, on the one hand, impedes or makes impossible the making of the contact on unintentional movement of the movable parts or equipment of the switch whereas by intentional movement of this equipment the impeding mechanism may be inactivated and the circuit breaker or switch at wish closed or opened, the great risks involved with an accidental closing of the contacts thus being avoided.

A further object of the invention is to apply this impeding mechanism to the actuating shaft of the movable equipment in such a manner that the mechanism is unidirectionally operative or effective, i. e., that the impeding mechanism distinguishes between movements in the opening sense and movements in the closing sense so as to allow the circuit breaker or switch to be opened unimpededly.

It is furthermore an object of the invention to render the impeding mechanism selective, so that it may select between movements of the movable equipment relatively to the stationary equipment of the switch when, on the one hand, through shock or vibration, the switch as a whole executes a coerced movement and through the inertia of the movable equipment a turning movement is produced at the shaft which would tend to close the switch and, on the other hand, when through intentional actuation of the actuating means, turning moments are produced at the shaft which tend to close or to open the circuit breaker. In the one case the impeding mechanism is to impede movement of the shaft, in the other case it is to release such movement.

The protecting device for circuit breakers with at least one contact pair having a stationary and a movable contact, a shaft carrying the movable contact, and actuating means for closing and opening the contacts, in accordance with the invention thus includes a unidirectionally selective impeding mechanism associated with the shaft.

This impeding mechanism is adapted for taking up turning moments caused, on coerced movement of the circuit breaker as a whole, through inertia of the movable contact and produced by, and arriving at the impeding mechanism from, movement of the movable contact relatively to the stationary contact and in the closing sense, unintentional closing of the contacts thus being avoided. The impeding mechanism is further adapted to release the shaft for movement by turning moments produced at the

shaft by intentional actuation of the actuating means for operation of the circuit breaker in either sense, opening and closing the contacts.

The impeding mechanism may be of various types. The mechanism may thus be unidirectionally responsive to angular displacement of the shaft in the closing sense. The mechanism will thus be unresponsive to movements of the shaft in the opening sense but will respond to angular displacement of the shaft in the closing sense and selectively will resist such movement during a first certain angle of this movement in the closing sense while it will release its resistance when the shaft has been moved above this angle. In this way unintentional closing of the contacts is prevented when the movable contact through its inertia moves out of its open position. The contacts however may be intentionally closed when, by means of the actuating means, the shaft is moved through and above this angle.

In an embodiment of this development of the invention, the mechanism which resists the unintentional closing of the contacts includes a stationary member, that is, stationary relatively to the stationary part or equipment of the circuit breaker, further includes a movable member disposed on the shaft and interengaging means which are unidirectionally responsive to angular displacement of the shaft in the closing sense. This resisting mechanism may include a brake mechanism with means which, during a first certain angle of displacement of the shaft relatively to the stationary parts of the circuit breaker, cause the brake members to engage each other and thus to brake and impede the movement of the shaft. These means, when through intentional operation of the shaft the resistance of the brake mechanism has been overcome and the shaft has moved through and above this angle, will then release the brake members from engagement and allow the shaft to be freely moved by the actuating means for closing the contacts.

By these means, the resisting mechanism may be so designed that the energy of even the greatest shock as might occur and act upon the movable equipment of the circuit breaker in the sense of closing the contacts is absorbed through the frictional moment before the fixed and movable main contacts or arcing contacts might touch each other. On the other hand, the action of the frictional moment ceases as soon as by intentional operation of the actuating means the angular displacement has reached a certain predetermined value and the frictional resistance on this path once has been overcome.

In another development of the invention the impeding device may include a locking mechanism comprising a stationarily mounted locking member and cooperating therewith a stop member mounted on, and secured to, the shaft and engaging the locking member in the "open" position of the shaft, i. e. the position of the shaft where the contacts are open. A release member is secured to the actuating means to be actuated thereby for lifting the locking member out of engagement with the stop member when the actuating means are moved in the sense to close the contacts. Coupling means are provided which, on disengagement of the locking mechanism, couple the actuating means and the shaft for closing the contacts by actuation of the actuating means.

Unintentional closing of the contacts out of the "open" position of the movable contact or

equipment is thus prevented how intensive the shocks or vibrations may be, but intentional closing and opening of the contacts is made possible without any hindrance.

In order to more clearly point out these and other features and objects of the invention, reference will now be made to the accompanying drawings which form part of this specification and which by way of example illustrate various embodiments of our invention. These drawings are to be understood explicative of the invention but not limitative of its scope.

Other embodiments incorporating the principle underlying our invention are feasible without departing from the spirit or ambit of our appended claims.

In the drawings:

Fig. 1 is an elevational front view of a switch with actuating means and protecting device of the invention embodied as a resisting mechanism, and more particularly a brake mechanism;

Fig. 2 is a similar view of the resisting mechanism of Fig. 1 partly in section, taken on line 2-2 of Fig. 4, and on an enlarged scale;

Fig. 3 is an elevational side view taken along line 3-3 of Fig. 1;

Fig. 4 is an elevational section, along line 4-4 of Fig. 1, the brake mechanism being in its disengaged position for a switch in its closed position;

Fig. 5 is the same sectional view, the brake mechanism being in its engaged position for the switch in its open position;

Fig. 6 is an elevational front view of a second embodiment of the invention embodied as a locking mechanism for a switch or circuit breaker for manual operation as well as for operation by remote control;

Fig. 7 is a side view taken along line 7-7 of Fig. 6 showing diagrammatically the switch or circuit breaker of Fig. 6;

Fig. 8 is a view similar to that of Fig. 6 partly in longitudinal section along line 8-8 of Fig. 9 of the locking device mechanism and on an enlarged scale;

Fig. 9 is a section along line 9-9 of Fig. 8;

Figs. 10 to 13 are side views of the manually operated part of the locking mechanism in various positions;

Fig. 14 is a diagrammatic perspective of the remote control part of the locking mechanism of Figs. 6 and 8;

Figs. 15 and 16 are side views of details of the remote control part of the locking mechanism.

In the embodiment shown in Figs. 1 to 5, a switch or circuit breaker of any type is schematically indicated at 11. 12 are the stationary contacts, 13 the movable contacts such as in the form of blades, knives, brushes, or the like. The shaft which carries the movable contacts or contact 13 is designated by 14.

The shaft 14 may be actuated by any convenient or conventional means, by remote control or, as indicated, by a handgrip 15.

Shaft 14, handgrip 15, and blades 13, in this instance, represent the movable equipment of the switch.

In this embodiment the unidirectionally selective impeding mechanism is a resisting mechanism with a stationary member, a movable member disposed on the shaft to be movable therewith, and with interengaging means responsive to angular displacement of the shaft in the closing sense.

In this instance of Figs. 1 to 5, where the re-

sisting mechanism includes a brake mechanism, the stationary member is the brake casing 18. The casing is fixed to the switch panel or other stationary structure, not shown, by a rod system including an adjustable rod 19 secured to casing 18 by means of a holding plate 20 riveted to the casing. The brake casing is rotatably carried on shaft 14 by means of a sleeve 21 with its one end extended into the casing 18 and provided at this end with a flange 25. At the other, the outside end, the sleeve is provided with a screw thread 22. Sleeve 21 furthermore is shaped with two flattenings 23, 24, at opposite sides, and the casing 18 is correspondingly perforated, so that casing 18 and sleeve 21 are keyed together in the peripheral direction but are displaceable relatively to each other in the axial direction.

An adjusting ring 26 is screwed on the sleeve and adjusted in its position by means of set screw 27 which sets on one of the flattenings, in the instance illustrated, the lower one, 24. Secured to the casing 18, for instance riveted, is a flanged bush 28, between whose flange 29 and the adjusting ring 26 a coil spring 30 is extended which thus urges the sleeve with its flange 22 towards the casing 18.

The movable member of the resisting mechanism is a carrier disc 31 which by means of a pin 32 is secured to shaft 14. Disc 31 carries a number of pawls 35, in the present instance three, evenly distributed over the circumference. The pawls 35 are freely turnable about their pivots 36. Springs 37, likewise attached to the carrier disc 31, urge the noses of the pawls towards the teeth of a ratchet wheel 38. The ratchet wheel 38 is provided at both its sides with annular discs 39, 40, of any conventional or convenient brake lining material. Together with these discs or brake linings ratchet wheel 38 is circularly perforated so as to be freely revolvable about sleeve 21.

An annular shoulder disc 41 is likewise keyed by the flattenings 23, 24, against peripheral displacement but axially displaceable on sleeve 21 and is seated between flange 25 and the adjacent annular disc or brake lining 39.

By means of spring 30 whose tension may be regulated by the setting of adjusting ring 26, the whole set consisting of discs 41, 39, 38, 40, is longitudinally compressed between flange 25 of sleeve 21 and the wall of the casing 18. In this brake assembly, shoulder disc 41 and casing 18 thus comprise the stationary brake member whilst the ratchet wheel 38 with its linings 39, 40 comprise the movable brake member. A strong braking effect will thus be produced between shoulder disc 41 and casing 18, on the one hand, and the two linings 39, 40, on the other hand, as soon as the movable brake member 39, 38, 40 starts turning relatively to the stationary brake member 41, 18.

The movable brake member 39, 38, 40, however, is not coupled with the shaft in a unique sense so that it would be coupled in any condition with the shaft and the carrier disc 31 of the resisting device thereon when the shaft 14 with this disc is turned clockwise, Figs. 4 and 5, or in the sense of arrow F in Fig. 2, the sense in which the circuit breaker is to be closed. The movable brake member rather forms part of the interengaging mechanism which imparts to the impeding or resisting mechanism unidirectional and selective characteristics.

Whereas the pawls ensure potentially that the shaft may be engaged with the brake when the shaft is turned in the closing sense, they ensure

also that the shaft remains disengaged from the brake mechanism when the shaft is turned in the opposite, the opening sense. The interengaging mechanism so far is unidirectional. But it is also selective through the following release mechanism operable through the angular displacement of the shaft.

This release mechanism comprises rollers 42 at the free ends of the pawls 35 which when riding on the inside surface of the cylindrical wall 44 of the casing 18 will lift the pawls 35 out of engagement with the ratchet wheel 38 but when reaching windows 43 provided in wall 44 will release the pawls 35 to be urged by the springs 37 into engagement with the ratchet wheel 38.

The pawls thus are so disposed at their carrier disc that the roller at the free end of each pawl may either ride on the cylinder wall of the casing and on and during contact with this wall 20 will lift the pawl nose out of engagement with the toothed rim of the ratchet wheel or that the roller on its path will find and enter a window and will thus release the pawl for engagement with the ratchet wheel.

25 The function of the device is as follows:

The casing 18, 44, with its windows 43 is so adjusted by means of the adjustable rod 19 that in the open position of the circuit breaker the rollers 42 of the pawls 35 may enter the windows 43.

30 If in this open position of the circuit breaker a shock or vibrations act upon the movable equipment of the switch and move blades 13 and hand-grip 15 of the movable equipment, these parts, since they are secured to the shaft, will take the 35 shaft 14 along and tend to turn it in the closing sense, arrow F in Figs. 2 and 4.

35 The disc 31 which is keyed to shaft 14 turns together with the shaft. Since the rollers 42 have entered the windows 43, the pawls 35 engage the 40 ratchet wheel 38, and tend to take it along.

The ratchet wheel however offers strong resistance to this movement in view of the great friction which is produced between the linings 39, 40, and the metal discs 14, 18, respectively. The 45 energy of the shock will thus be absorbed by friction.

The pressure of spring 30 and the peripheral 50 lengths of the windows are so determined that intensity and duration of friction suffices to absorb the greatest shock energy which might occur. It is obvious that the absorption of the shock 55 energy must be accomplished principally by the intensity of the friction and that therefore a very strong spring 30 is to be applied since the length of time during which the friction is effective corresponds to the angular displacement of disc 31 during which displacement the rollers 42 may move along the windows and, moreover, the displacement itself is to be limited to a certain, 60 relatively narrow angle in order to exclude with certainty any accidental contact between the main contacts or the spring contacts.

When the energy of the shock or of the vibrations has been absorbed, the movable equipment 65 will, unimpeded by the pawl and ratchet mechanism return into its rest or "open" position.

The frictional moment produced in the brake 70 mechanism is of course to be overcome when the switch or circuit breaker is to be closed intentionally. If the brake mechanism were to be operative over the whole angular displacement of the switch from the "open" to the "closed" position, this would tend to slow down the closing movement, whereas, to the contrary, the movable 75 contacts, at the moment of closing, should have

a very great velocity. The invention therefore provides, that after a certain time, or after a certain angle of travel has been completed, the effect of the frictional moment ceases. This end is achieved by determining and disposing the peripheral lengths of the windows in relation to the uninterrupted peripheral lengths of the cylinder walls, from window to window, so that as soon as the angle corresponding to the peripheral length of a window and provided for the absorption of the shock energy has been traversed, the rollers reach the uninterrupted arc of the cylindrical wall 44, are pressed inwards while continuing their course. The pawls 35 will now be pivoted about their pivots 36 and their noses will thus be lifted out of engagement with the ratchet wheel 38. The ratchet wheel will no longer be turned, the frictional moment vanishes, and the closing movement may be completed without any further hindrance.

The duration of the frictional coupling may be regulated through adjustment of the position of the casing 18 by varying the length of rod 19 and thus changing the position of the rollers 35 in the "open" position relatively to the edges of the windows 43 and correspondingly the magnitude of the angular displacement during which the frictional moment or couple is effective.

It will readily be appreciated that the device as just described may absorb not only the energy of an accidental shock but also that of oscillations of a certain range. As soon as the undesired or unintentional influences have ceased, the shaft will return under the influence of the gravity of the movable equipment into the normal "open" position of the circuit breaker or switch and the device is again ready for function.

Figs. 6 to 16 illustrate an embodiment wherein the shaft which carries the movable contacts or contact and the actuating means will be coupled together for actuation and will then be disconnected from one another. In this embodiment the device which protects the switch or circuit breaker against unintentional closing through inertia of the movable equipment and caused by coerced movement of the circuit breaker as a whole, includes a locking mechanism for locking the shaft against unintentional movement.

Fig. 11 again indicates schematically a switch or circuit breaker of any type with the stationary contact or contacts 12 and the movable contact or contacts 13, carried by the shaft 51.

In this embodiment the means for operating the switch manually is the handgrip 62 and the actuating means for remote control are an electromagnet 74 with armature 75, levers 77 and 82, and sleeve 83, as may be seen from Figs. 6, 8, and 9, the details of the members for manual control being shown in Figs. 10 to 13 and those for remote control in Figs. 14 to 16.

The locking mechanism which prevents the switch from being closed unintentionally and which locks the shaft 51 and thus the movable equipment from being moved, until by intentional actuation of the actuating means, manually or by remote control, the locking mechanism is released, comprises a locking member in form of a locking bar 52 pivotally mounted at 54 upon a stationary support 53. Support 53 is secured by any conventional means, not shown, to the panel of the switch or other structure supporting the same. A leaf spring 57 secured to the support urges the locking bar 52 upwards against a stop member in form of a cam 55 mounted upon and secured to shaft 51. Cam 55 of generally

70 semi-circular contour is shaped with a notch or indentation 56 into which the locking bar 52 will enter when shaft 51 is in the open position of the circuit breaker or switch. Notch or indentation 56 will thus serve as a stop, preventing shaft 51 from being unintentionally moved in the closing sense until, on intentional actuation of the actuating means for closing the switch, proper release mechanism will lift or pivot the locking bar 52 out of engagement with notch or indentation 56 of the stop member or cam 55, and coupling means will thereon couple the actuating means with shaft 51, as will be described hereinafter.

15 The release members for the locking bar 52 are two cams 59 and 60 both loosely mounted on shaft 51. One cam, 59, for manual operation is secured to the handgrip 62, loosely mounted on shaft 51, the other cam 60, for remote control is secured to sleeve 83 likewise loosely mounted on shaft 51.

20 In the rest position of the circuit breaker where both, handgrip 62 and sleeve 83, are uncoupled or disconnected from the shaft and are loosely movable thereon, the cams 59 and 60 through their shapes are disengaged from the locking bar 52. On being pivoted about axis 51, each cam, independently of the other, will strike against the locking bar 52 and thereby tilt against the tension of spring 57 the locking bar about pivot 54 out of the indentation or notch 56 of stop cam 55.

25 Handgrip 62 terminates in a fork 63 by means of which it is loosely mounted on shaft 51. Cam 59 is secured, by soldering, brazing, or welding, for instance, to one branch of the fork.

30 The branches of fork 63 embrace cam 55 and opposed thereto carry a pawl 64 loosely pivoted at 65. The pawl 64 is so suspended that its center of gravity is below its pivot 65, as shown in the rest position of handgrip 62 is Fig. 9, and where the pawl bears with its tail end against an abutment pin 66 which prevents undesired deflection of the pawl in the one direction.

35 The upper contour 67 of the pawl is so shaped that in this position, Fig. 9, the pawl just clears the unindented semi-circular contour of cam 55, so that this cam may unimpededly pass the pawl when the cam is turned together with shaft 51 by actuation of the remote control device which will be described in detail later on.

40 When the switch is to be closed, the handgrip 62 is moved from its rest position, Fig. 9, upwards in the sense of arrow F. The cam 59 will strike against the locking bar 52 and tilt it in the sense of arrow K, Fig. 10, out of engagement with indentation 56 of cam 55.

45 Cam 55 and together with it shaft 51 are thus released for movement or actuation in the closing sense. On further movement of the handgrip 62 and when the handgrip has reached the position of Fig. 10, the arc contour of cam 55 will hold the locking bar disengaged. The upper contour of the pawl will no longer be guided along the contour of cam 55 and no longer be held with its tail end against abutment pin 66, but will by its gravity turn about pivot 65 and snap with a corner notch 68 over edge 69 of cam 55.

50 By moving the handgrip downwards in a sense opposite that of arrow F into the position shown in Fig. 11, a position of handgrip 62 beyond its normal rest position, the switch is closed. The handgrip may now be released and will thus fall into its loose, rest position

where the pawl is disengaged from cam 55 and likewise takes its loosely suspended rest position, Fig. 12.

When the switch or circuit breaker is to be opened, the handgrip is lifted again, in the drawing counterclockwise, until the front edge of the fork 63 abuts against a pin 79 provided in an extension 11 at the top edge of cam 55. On further movement in the sense of arrow G, Fig. 13, handgrip 62, now coupled with shaft 51, opens the switch while cam 55, with the movement of shaft 51, is returned into its original rest position where the locking bar 52 again engages the indentation 56, engagement which will only transitorily be lifted when handgrip 62 is returned into its original rest position and on its passage contacts with its cam 59 the locking bar shortly.

All parts are thus returned into the original rest position of Fig. 9.

The arrangement and the functioning of the remote control mechanism will now be described.

Lever 77 which is pivoted to a stationary pivot 79 is linked by means of rod 76 and pivot 78 to the armature 75 of the electromagnet 74 for remote control. The free end 80 of lever 77 is formed as a hook against which bears the end 81 of a lever 82 secured to sleeve 83. The other end 85 of lever 82 is forked. The fork 85 embraces with clearance a crank pin 89 of a crank arm 88 which is secured to shaft 51.

The masses of the hook lever 77, as Fig. 14 likewise illustrates, are so distributed that the center of gravity is eccentric with regard to the link pivot 78 and is lying above the same so that the moment of gravity of the top heavy hook lever 77 pulls the armature 75 out of the electromagnet 74 when the electromagnet is unexcited.

Lever 82, 85, is so shaped, as Figs. 9 and 14 illustrate, that its center of gravity is eccentric and is lying towards the fork side of lever 82 so that the resulting moment of gravity will tend to turn lever 82 and with it sleeve 83 in a sense opposite to that of arrow H, or counterclockwise. Lever 82, 85, is secured to sleeve 83 and crank 88, 89, to shaft 51 so that in the "open" position of shaft 51, where the locking bar 52 engages the indentation 56, lever 85, bearing with its end 81 against hook 80 of lever 77, will by means of sleeve 83 hold cam 60 in the position shown in Fig. 15, where the deepest point or indentation 92 of the cam rise 93 just contacts but does not deflect the locking bar 52. In this position of lever 82, the upper branch of fork 85 will be pulled, as Fig. 14 likewise illustrates, by the resulting moment of gravity, to bear against the crank pin 89, these end positions of hook lever 77 and lever 82 being secured by a proper abutment for any one of the members, for instance, for the stroke of the armature 75, as indicated at 94.

Instead of the aforesaid distribution of the masses or shaping of lever 82 for obtaining the desired moment, in the drawing in the sense opposite to that of arrow H, or counterclockwise, or in addition thereto, one or more springs may be provided at the members such as a spring 95 at the lower branch of fork 85.

Since in the open position of the switch, shaft 51, which carries the movable equipment 13 of the switch, is securely locked against any unintended movement through the locking bar 52 engaged in the indentation 56 of cam 55 secured to shaft 51, no shock or vibrations which

might impart to the switch or circuit breaker as a whole a coerced movement, may cause any movement of the movable equipment, through its inertia, relatively to the stationary part or equipment of the circuit breaker or switch. Any risk that the switch or circuit breaker might be inadvertently or unintentionally closed is thus avoided.

Intended closing of the switch, however, may be achieved simply by manipulating the handgrip 62, in the case of manual operation as described hereinbefore, or, in the case of remote control, by exciting the electromagnet 74.

The same as the closing by hand, the closing by remote control comprises two phases. The first phase in which the shaft 51 is unlocked and the second phase in which the switch is closed by turning the shaft.

In the first phase, electromagnet 74 as soon as it has been excited, by means of its armature 75, withdraws rod 76 and tilts hook lever 77 about pivot 79.

Hook 80 deflects the fork lever 82 clockwise, in the sense of arrow H. The fork 85, before it strikes crank pin 89, moves first idly, a path "a," Fig. 14, a path which corresponds to the clearance between the fork branches and crank pin 89, see also Fig. 16. During this movement of lever 82, sleeve 83 together with cam 60 is turned clockwise and the cam rise 93 of cam 60 will rock the locking bar 52 and lift the bar out of engagement with the indentation 56 of cam 55, and will then hold the locking bar in inactive position, out of engagement, on the circular circumference of cam 60. Cam 55 and with it shaft 51 are thus released for movement or actuation in the closing sense, unimpeded also by the cam mechanism operable by the manual actuating means.

In the second phase of the rocking movement of fork 85, its lower branch will strike against the crank pin 89 and thus oscillate crank 88 with shaft 51. Cam 55 of shaft 51 will with the circular part of its circumference continue to hold the locking bar 52 disengaged and shaft 51 will move the movable equipment into the "closed" position of the switch or circuit breaker.

When the electromagnet is de-energized, the hook lever 77 by gravity will return into the position of Fig. 14 pulling with it the armature 75 of the electromagnet 74. The end 81 of the fork lever 77 through its moment of gravity or pulled by spring 95 or both, in the first phase of its return movement, will, by means of sleeve 83, move cam 60 back towards the position of Fig. 15, until the upper end of cam rise 93 is opposite the locking bar 52, this bar however still being held inactive, out of engagement, by cam 55.

In the second phase of the return movement, when the upper branch of fork 85 has reached crank pin 89, the fork lever, on further return movement, counterclockwise, simultaneously brings the indentation 92 of cam 60 in opposition to the locking bar, turns shaft 51 thus opens the switch or circuit breaker and with shaft 51 turns cam 55 into the initial position where the locking bar 52, now opposite indentation 92 is unimpeded by cam 60 and may engage the indentation 56 of cam 55, thus locking again the movable equipment, in the "open" position of the switch or circuit breaker, against unintended movement in the closing sense.

We claim:

1. Protecting device for circuit breakers with at least one contact pair having a stationary contact and a movable contact, a shaft carrying

said movable contact, and actuating means for closing and opening said contacts; said device including a unidirectionally selective impeding mechanism having a movement resisting member mounted at said circuit breaker independently of said shaft, a member rigidly secured at said shaft to be movable therewith and adapted for unidirectional engagement with said resisting member thereby to take up turning moments caused on coerced movement of said circuit breaker as a whole through inertia of the movable contact and produced by, and arriving at said impeding mechanism from, movement of the movable contact, and resist any unintentional closing movement of the contacts; said impeding mechanism further including release mechanism associated with said actuating means and operable thereby for disengaging said shaft member from said resisting member and thus to release the shaft for movement by turning moments produced at the shaft by intentional actuation of the actuating means for operation of the circuit breaker in either sense, opening and closing the contacts.

2. Protecting device for circuit breakers with at least one contact pair having a stationary contact and a movable contact, a shaft carrying the movable contact and actuating means on the shaft for closing and opening the contacts by means of the shaft; said device having a resisting mechanism including a stationary member, a movable member disposed on the shaft and rigidly secured thereto so as to be movable therewith, and interengaging means between both said members and operatively connected therewith and resistantly movable with relation thereto, unidirectionally responsive to angular displacement of the shaft in the closing sense thereby to interengage the stationary and movable members and to resist angular displacements of the shaft during a first certain angle of its closing movement; said stationary member including release mechanism associated with said movable member and adapted to become operative on movement of the shaft above said angle; thereby to prevent unintentional closing of the contacts on movement of the movable contact through its inertia out of the open position and caused by coerced movement of the circuit breaker as a whole, but to allow intentional closing of the contacts and unimpeded opening of the same, and at the end of the opening movement to bring the stationary and the movable members again into position for interengagement.

3. Protecting device for circuit breakers with at least one contact pair having a stationary contact and a movable contact, a shaft carrying the movable contact and actuating means on the shaft for closing and opening the contacts by means of the shaft; said device having a brake mechanism with two brake members movable relatively to each other, both loosely disposed on the shaft, one being stationary the other movable relatively to the stationary brake member and the shaft; said device further including mechanism for unidirectionally interengaging the movable brake member and the shaft responsive to angular displacement of the shaft in the closing sense thus to absorb by friction the energy of such angular displacement; said device further including release mechanism associated with the shaft and adapted to become operative on movement of the shaft above a certain angle and to release the brake mechanism; thereby to prevent unintentional closing of the contacts on

movement out of the open position of the movable contact through its inertia and caused by coerced movement of the circuit breaker as a whole but to allow intentional closing of the contacts and unimpeded opening of the same, and at the end of the opening movement to bring the stationary and movable brake members again into position for interengagement.

4. Protecting device as set forth in claim 3 wherein said interengaging mechanism comprises a pawl and ratchet wheel gearing; said ratchet wheel being secured to the movable brake member; a carrier disc mounted on the shaft and secured thereto, the pawl being pivotally mounted on the carrier disc, spring means, associated with the pawl, being secured to the carrier disc and adapted to urge the pawl at the one end thereof into engagement with the ratchet wheel, stationary control means being associated with the other end of the pawl and adapted to release the pawl on a certain angle of its rotary movement with the carrier disc and shaft, out of the open position of the contacts, for engagement with the ratchet wheel, and, on rotary movement above said angle, to lift the pawl out of engagement with the ratchet wheel.

5. Protecting device as set forth in claim 4 wherein said stationary control means includes a stationary cylindrical casing loosely disposed on the shaft and with its cylindrical wall surrounding said carrier disc, the free end of the pawl being disposed and adapted to ride on the inside surface of said cylindrical wall, the pawl on contact with the wall thereby being lifted out of engagement with the ratchet wheel, windows being provided in said wall and on the path of the pawl, the peripheral lengths of the windows being determined and disposed in relation to the uninterrupted peripheral length of the wall from window to window so as to release the pawl for engagement with the ratchet wheel on said certain angle of the shaft angular displacement.

6. Protecting device as set forth in claim 5 wherein a sleeve is mounted on the shaft, loosely enclosing the same, the movable brake member and the ratchet wheel being loosely mounted on the sleeve and the cylindrical casing keyed thereto against rotational displacement, thereby to hold the sleeve against angular displacement.

7. Protecting device as set forth in claim 6 wherein said sleeve is axially displaceable relatively to the casing and has a flange at its one end, disposed within the casing, the movable brake member and the ratchet wheel being housed within the casing and disposed between the end wall thereof and said flange of the sleeve; an adjusting ring being disposed on the other end of the sleeve, a coil spring being disposed between the adjusting ring and the end wall of the casing outside thereof; thereby to press the movable brake member between the end wall of the casing and the flange of the sleeve and to set the frictional resistance of the brake mechanism.

8. Protecting device for circuit breakers with at least one contact pair having a stationary contact and a movable contact, a shaft carrying the movable contact and actuating means associated with the shaft for closing and opening the contacts by means of the shaft; said device including a locking mechanism having a locking member, a stationary support for carrying the locking member, a stop member mounted on and secured to the shaft and associated with the locking member for engaging the same in the "open" position of the shaft thereby to prevent movement

of the shaft in the closing sense; said device further including a release member secured to, and adapted to be actuated by, said actuating means, the release member being associated with the locking member and adapted to lift the locking member out of engagement with the stop member on movement of the actuating means in the closing sense; and coupling means associated with the release member, the shaft, and the actuating means and adapted, on disengagement of the locking mechanism, to couple the actuating means and the shaft for closing the contacts by actuation of the actuating means; thereby to prevent unintentional closing of the contacts out of the open position of the movable contact through its inertia, on coerced movement of the circuit breaker as a whole but to allow intentional closing and opening of the contacts, and at the end of the opening movement to bring again the locking member into engagement with the stop member.

9. Protecting device as set forth in claim 8 wherein said locking member is a bar mounted on said support, and the stop member is a cam with a stop thereon mounted on and secured to the shaft, a spring being provided at the support disposed and adapted to urge the locking bar against the stop cam.

10. Protecting device as set forth in claim 9 wherein said actuating means is provided with a release cam loosely mounted on the shaft and adapted for cooperation with the locking bar, thereby, on actuation of the actuating means, to lift the locking bar out of engagement with the stop of the stop cam.

11. Protecting device as set forth in claim 8 wherein said actuating means comprise switch-

ing means for manual operation and switching means for remote control; each separately provided with a release cam secured thereto and separately loosely mounted on the shaft; the locking member being a bar pivotally mounted on said support; said stop member being a cam with a stop thereon and mounted on and secured to the shaft, a spring being provided at said support disposed and adapted to urge the locking bar against the stop cam; the release cams being adapted for cooperation with the locking bar, thereby, on actuation of any of said two switching means to lift the locking bar out of engagement with the stop of the stop cam.

12. Protecting device as set forth in claim 8 wherein said release member is rotatably mounted on the shaft and the coupling means include abutment means mounted to the shaft and cooperating abutment means at said actuating means, both disposed and arranged to provide for free motion of the actuating means relatively to the abutment of the shaft; thereby to make it possible, on closing movement of the actuating means, first to disengage the locking member from the stop member and thereon, on further movement of the actuating means, to engage by means of the abutments the actuating member with the shaft and close the contacts.
